UNITED STATES PATENT OFFICE

HUBERT ZINS, OF WABASSO, MINNESOTA

VETERINARY CASTRATING INSTRUMENT

Application filed July 31, 1930. Serial No. 472,111.

This invention relates to an instrument adapted primarily for castrating animals such as cattle and sheep and it aims to provide a novel means whereby the result may be accomplished without inflicting external wounds but rather to crush or sever the spermatic cord and leave the testicles in situ where they will atrophy away and thereby render the male animal infertile.

10 It is particularly aimed to provide an instrument which is exceedingly simple and accurate, will enable the operation to be performed rapidly, has novel means for holding the cord while crushing it and a tool which 15 will make it safer in castrating and to enable the animal to recover without any loss from septicemia or infection.

The more specific objects and advantages 20 will become apparent from a consideration of the description following taken in connection with accompanying drawings illustrating an operative embodiment.

In said drawings:

25 Figure 1 is a view illustrating the improved instrument in elevation, portions of the same being broken away to disclose details,

Figure 2 is a sectional detail taken on the line 2—2 of Figure 1,

30 Figure 3 is a cross sectional view taken on the line 3—3 of Figure 1,

Figure 4 is a cross sectional view taken on the line 4—4 of Figure 1,

Figure 5 is a view somewhat similar to 35 Figure 1 but showing the parts separated,

Figure 6 is a sectional view taken on the line 6—6 of Figure 1,

Figure 7 is a sectional view taken on the line 7—7 of Figure 1, and

40 Figure 8 is a detail perspective view of a portion of the operating lever.

Referring specifically to the drawings, 10 designates a relatively fixed bar member and 11 a relatively movable bar member, such members respectively having lateral or offset jaws as at 12 and 13, respectively. Prongs 14 extend forwardly from the jaw member 13 and beyond the same and are fastened in place by removable and adjustable bolts 15. The portion of the jaw 13 through which the 45 bolts pass is triangular in cross section as

shown in Figure 2 and resilient blocks 16, which may be separate as shown or in a single piece as preferred, are interposed between the prongs 14 and the jaw 13, the fit of the prongs 14 on the bolts being rather loose 55 whereby the free ends of such prongs 14 may spread or separate as permitted and cushioned by the resilient blocks 16.

The jaws, in the open position, as shown in Figure 5, are adapted to be placed over 60 the spermatic cord which is held with the left hand against the outer wall of the scrotum and well above the testicle, the prongs 14 receiving the cord between them and the jaw 13 then being moved backwardly and 65 forwardly in order to crush the cord without danger of slipping or disengagement, against the jaw 12. Since the prongs 14 are movable toward and away from each other and cushioned by the blocks 16, they are automatically 70 adjustable according to the thickness of the skin which they engage.

The bar member 10 is rigid with a hollow handle portion 17, preferably being fastened 75 to the top wall 18 thereof. A guide of U-shape surrounds the bar members 10 and 11 and is riveted or bolted to the latter as at 19. The bar member 11 is slidable against the under surface of the wall 18 and has a guide and operating member 20 which is slidable 80 through the front wall 21 of the handle 17. A knob or manual grip 22 is provided on the end of the member 20.

A trigger or operating lever 23 is connected to a U-shaped member 24 which is pivoted at 25 to the handle portion 17. The under surface of the bar 11 is toothed or serrated as at 26 and the same is engageable by teeth 27 and 28, of pawls 29 and 30, respectively. Pawl 29 is pivoted at 31 to the lever member 24 while the pawl 30 is pivoted at 32 to the handle 17. Pawl 30 has an elongated member or tine 33 which is engaged by a cross member 34 suitably fastened to the lever 24. A leaf spring 35 fastened to the handle 17 constantly urges the pawl 30 into engagement with the cross member 34. The cross member or abutment 36 is provided on the handle 17 for the pawl 29 and a leaf spring 37 secured to such handle urges the 100

pawl 29 against the abutment 36 and into locking engagement with the teeth 26.

As a result of the construction described, the lever 23 may be thrown forwardly relatively to the handle portion 17 which results in disengaging the pawls 29 and 30 from engagement with the teeth 26. Thereupon the knob 22 may be engaged to move the jaw member 13 away from the jaw member 12 in order 10 to receive or engage the spermatic cord between the jaws. The bar 11 is then moved forwardly to engage the cord between the jaws 12 and 13 and prongs 14. Then by moving the lever 23 towards handle 17 by gripping it 15 with the fingers of one hand, the other hand holding the jaws and spermatic cord in position, the teeth 27 of pawl 29 will push jaw 13 against the cord and jaw 12 and by moving lever 23 backwardly and forwardly the pressure will be increased and the cord crushed, 20 the tooth 28 of pawl 30 holding the bar from rearward movement during said movements of the lever.

It will be realized that my means of the 25 present invention, the spermatic cord is secured or held against displacement before any pressure is applied to the cord in order to separate or crush it.

It will be realized that after completing 30 the operation relative to one cord, the instrument is disengaged and turned approximately one hundred and eighty degrees whereupon the same procedure as previously described, is followed with respect to the 35 other cord.

Various changes may be resorted to provided they fall within the spirit and scope of the invention.

I claim as my invention:—

40 1. In a castrating instrument, a pair of jaws to engage a spermatic cord, means on one of the jaws extending beyond the plane of engagement thereof with the cord, to prevent disengagement therewith, means permitting relative movement of the first mentioned means to accommodate two thicknesses of the skin between the jaws, comprising a pair of prongs, means securing the same to one of the jaws for movement toward and 50 away from each other and cushioning means against which the prongs operate.

45 2. An instrument of the class described comprising a pair of bar members, jaws on said members, a handle to which one of said members is secured on one side thereof, the second member being slidably mounted in the handle and movable relatively to the first member, teeth on the second member, a lever cooperating with the handle, a pawl 55 associated with said lever and with said teeth so that operation of the lever will move the movable member and jaw relatively to the other jaw, said pawl being disengageable from the second member to permit manual 60 operation of the latter.

3. An instrument of the class described comprising a pair of bar members, jaws on said members, a handle to which one of said members is secured on one side thereof, the second member being slidably mounted in 70 the handle and movable relatively to the first member, teeth on the second member, a lever cooperating with the handle, a pawl associated with said lever and with said teeth so that operation of the lever will move the movable member relatively to the other member and jaw, said pawl being disengageable from the second member to permit manual operation of the latter, a manually operable element extending from the second member 75 and through the handle to actuate said member alternatively with said lever, and a guide carried by one of the members and surrounding the other member beyond the forward extremity of the handle.

In testimony whereof I affix my signature.
HUBERT ZINS.
